UNITED STATES PATENT OFFICE.

BERNARD P. WAGNER, OF SIDNEY, OHIO, ASSIGNOR TO THE WAGNER MANUFACTURING COMPANY, OF SIDNEY, OHIO, A CORPORATION OF OHIO.

DESIGN FOR A TEA-KETTLE.

49,718.

Specification for Design. Patented Sept. 26, 1916.

Application filed July 3, 1916. Serial No. 107,473. Term of patent 14 years.

To all whom it may concern:

Be it known that I, BERNARD P. WAGNER, a citizen of the United States, and resident of Sidney, county of Shelby, and State of Ohio, have invented a new, original, and ornamental Design for a Tea-Kettle, of which the following is a specification, reference being had to the accompanying drawing, forming part thereof.

In said annexed drawing:—Figure 1, is a side elevation; Fig. 2 is a front elevation and Fig. 3 is a plan view of a tea kettle, showing my new design.

I claim:—

The ornamental design for a tea kettle, as shown.

Signed by me this 30 day of June, 1916.

BERNARD P. WAGNER.

Attested by—

ROYON G. NESS,
FLORENCE SMITH.
